ATTORNEY

UNITED STATES PATENT OFFICE.

WILLIAM G. MENNEN, OF NEWARK, NEW JERSEY.

CARDBOARD POWDER-BOX.

1,295,997.

Specification of Letters Patent.

Patented Mar. 4, 1919.

Application filed November 22, 1918. Serial No. 263,704.

To all whom it may concern:

Be it known that I, WILLIAM G. MENNEN, a citizen of the United States, and resident of Newark, in the county of Essex and State 5 of New Jersey, have invented certain new and useful Improvements in Cardboard Powder-Boxes, of which the following is a specification.

This invention comprises certain improvements upon and within the invention in cartons of my prior application, Serial No. 215,067, filed February 2, 1918. The present objects are to cheapen and simplify the manufacture and to secure a better sealed 15 joint between the body and the filling opening disk.

In the accompanying drawings illustrating two forms of the improvements:

Figure 1 is a perspective view of the 20 carton;

Fig. 2 is a vertical section through the assembled carton;

Fig. 3 is an inverted perspective view of the cover;

Fig. 4 is a top perspective view of the inner shell of the body;

Fig. 5 is a fragmentary inverted perspective view of the same;

Fig. 6 is a perspective view of the outer 30 shell of the body;

Fig. 7 is a perspective view of the closure disk;

Fig. 8 is a vertical section through another form of the carton;

Fig. 9 is a perspective view of the innermost shell of the body of this form;

Fig. 10 is a perspective view of the cover;

Fig. 11 is a perspective view of the two shells, constituting the inner portion of the 40 body of Fig. 8, assembled;

Fig. 12 is a perspective view of the outermost shell of this body;

Fig. 13 is a perspective view of a closure and sifter disk; and

Fig. 14 is a perspective view of the intermediate shell, that is to say the outer of the two shells forming the body in this instance.

In Figs. 2 and 8 the layers are shown 50 separated for clearness of illustration, but in actual fact, of course, they lie close together and the various layers of the body are cemented together.

As in my other application the carton is 55 designed more particularly as a retail sifter package for talcum powder. The advan-

tages of the features common to both cases are set forth in the said application and need not be repeated.

Reference will first be had to Figs. 1 to 7. 60

The body of this form comprises two tubular cardboard shells 2 and 3, preferably of oblong cross-section, 2 being the inner shell and 3 the outer shell. The two shells are telescoped and glued or cemented together. 65 The inner shell is of suitable length to project a distance above the outer shell to form a neck for the reception of a slip cover 4. At the bottom the outer shell projects slightly below the inner shell, forming a bottom recess. A cardboard disk or brace 6 containing a large filling opening 9 is placed against the lower end of the shell 2; and when the box is filled through this opening 70 a closure disk 8 is inserted into the bottom recess, filling the same, and is glued in place.

In my prior application a finishing sheet covering the outside of the body was turned up on the inner surface of the projecting lower end of the outer shell and then carried 80 across on the bottom of the filling opening disk, to hold the latter in place. In the present instance I provide each of the shells 2 and 3 with its own finishing sheet. The finishing sheet 5 of the outer shell covers 85 the latter and is turned in at the ends. The finishing sheet 25 which is pasted around the inner shell is turned inward at 7 and glued upon the under face of the apertured disk 6 around the opening. This same sheet may 90 be extended all the way to the top of the inner shell to form a finish for the neck which receives the slip cover 4. The cover may also have a separate finishing sheet 15 and be secured in place by a paster or label 95 26, or one finishing sheet may surround and temporarily unite both the body and the cover as in my other application.

By the present construction the manufacture of the box is simplified and the joint 100 between the filling opening disk 6 and the shell 2 is sealed in such manner as materially to reduce the possibility of leakage.

The top wall 10 of the inner shell is provided with perforations 11 to constitute a 105 sifter, the perforations being covered by a sheet 12, preferably transparent, which the user punctures.

In Figs. 8 to 14 the outer shell 3^a has a permanent bottom 10^a. The inner portion 110 of the body comprises two tubular shells 2^a and 2^b. These shells are telescoped into

each other and cemented and both are cemented into the outer shell. The inner portion of the body projects above the outer shell to receive the slip cover 4^a, as in the other form. A disk 6^a having a filling opening 9^a is applied to the upper end of the innermost shell 2^b, and a closure disk 8^a is cemented into a top recess formed by a slight projection of the shell 2^a above the shell 2^b. The closure disk 8^a is provided with sifter openings 11^a, temporarily closed by a sheet 12^a.

A special finishing sheet 25^a is glued around the innermost shell 2^b and its extension 7^a is turned over and glued to the top of the filling opening disk 6^a, for the same purpose as the sheet 25 of the other form. The outer shell 3^a has a finishing or covering sheet 5^a, the cover has a special finishing sheet 15^a, and the intermediate shell, or the upper portion thereof, is preferably covered by still another finishing sheet 5^b.

With this form of box, the body is assembled complete by the box manufacturer, with the exception of the closure and sifter disks 8^a, these and the covers being furnished separately. The powder manufacturer fills the bodies through the top, glues in the closure and sifter disk, and applies the cover.

In Figs. 1 to 7, the body and the cover are assembled complete by the box manufacturer, with the exception of the bottom closure disk 8, as in my other application.

What I claim as new is:

1. A carton of the kind comprising a body formed of inner and outer cardboard shell portions telescoped and united with the inner portion projecting above the outer portion, a slip cover for the top projecting portion of the inner portion, one end of the body being closed by an end wall, a disk in the other end of the body containing a filling aperture, and a closure disk which is cemented over said disk with filling aperture when the box is filled, characterized by the innermost shell having a special finishing sheet which is applied to its outer surface and extended over on the disk with

filling aperture to hold the same in place and to seal the joint.

2. A carton of the kind comprising a body formed of inner and outer cardboard shell portions telescoped and united with the inner portion projecting above the outer portion, a slip cover for the top projecting portion of the inner portion, one end of the body being closed by an end wall, a disk in the other end of the body containing a filling aperture, and a closure disk which is cemented over said disk with filling aperture when the box is filled, characterized by the inner portion of the body comprising two shells, the innermost shell bearing the disk with filling aperture at the top and having its own special finishing sheet which extends over said disk and seals the joint.

3. A carton of the kind comprising a body formed of inner and outer cardboard shell portions telescoped and united with the inner portion projecting above the outer portion, a slip cover for the top projecting portion of the inner portion, one end of the body being closed by an end wall, a disk in the other end of the body containing a filling aperture, and a closure disk which is cemented over said disk with filling aperture when the box is filled, characterized by the inner portion of the body comprising two shells, the disk with filling aperture being at the top of the innermost shell, and the closure disk having sifter openings therein.

4. A carton of the kind comprising a body formed of inner and outer cardboard shell portions telescoped and united with the inner portion projecting above the outer portion, a slip cover for the top projecting portion of the inner portion, one end of the body being closed by an end wall, a disk in the other end of the body containing a filling aperture, and a closure disk which is cemented over said disk with filling aperture when the box is filled, characterized by the disk with filling aperture and the closure disk being at the top of the body and the closure disk being provided with a sifter.

WILLIAM G. MENNEN.
